Patented Oct. 22, 1912.

UNITED STATES PATENT OFFICE.

WILLIAM H. CLEMENTS, OF NUTLEY, NEW JERSEY.

DISPLAY-CONTAINER.

1,042,086.

Specification of Letters Patent.

Patented Oct. 22, 1912.

Application filed January 9, 1912. Serial No. 670,293.

To all whom it may concern:

Be it known that I, WILLIAM H. CLEMENTS, a citizen of the United States, residing at Nutley, in the county of Essex and State 5 of New Jersey, have invented certain new and useful Improvements in Display-Containers, of which the following is a specification.

This invention relates to display devices 10 and particularly to containers for displaying samples of merchandise and the like.

The principal object of the invention is to provide a container of this kind with a transparent cover whereby the goods 15 closed in the container will be exposed to clear view and will yet be protected against being handled or from becoming displaced from the container, while at the same time the cover may be readily removed from and 20 as readily reassembled with the body part of the container, the parts being so formed and arranged that the improved container is simple, compact and durable in construction.

The invention is illustrated in the accompanying drawing in reference to a container 25 of the kind suitable for use in a folding sample case operating on the lazy-tong principle, Figure 1 being a perspective view of two of the containers, adapted to such use, constructed in accordance with this invention; Fig. 2 a perspective view of parts of the body structure of the improved container, separated from each other; Fig. 3 a 30 transverse sectional view of the container of Figs. 1 and 2; Fig. 4 a transverse sectional view of the container somewhat modified; and, Fig. 5 shows the cover detached.

The drawing shows the preferred construction, but it should be understood that I 40 am not limited to any of the details therein shown or herein described for the purpose of illustration.

a is a rectangular box-like body structure 45 for receiving the goods to be displayed. It has a bottom and four upright walls, the two side walls b b of which are preferably cut low, the object of which is to increase the exposure of the contents to view, and the two end walls c c of which are provided with the 50 inwardly extending lips or projections d d which serve not only to support the next subjacent container when the series shown in Fig. 1 is collapsed into vertically disposed relation but in the interlocking of the cover 55 and body structures together, as will herein-after appear. The side walls may, if de-

sired, be left the same height as the end walls, as at e in Fig. 4.

To form the cover structure I provide a rectangular piece f of transparent, rather 60 stiff but flexible material such as transparent celluloid, and bend or fold it along parallel lines, as at g, the dimensions of the piece being such that when thus shaped its length will be but a trifle shorter and its width but 65 a trifle less than the corresponding dimensions of the body structure, while its height will be but slightly less than that of said body structure. This piece then includes the transparent integral top wall h and two 70 side or upright walls i i depending therefrom. The cover structure, thus formed, is assembled with the body structure as follows: Its sides i i are first slipped into place so as to stand at the inner sides of the corresponding walls of the body structure and, having now introduced one end of its top wall under one of the lips d d, the other end is sprung under the opposite lip, this 75 being permitted by the flexibility of the material which, being also elastic, at once resumes its normal shape when finally the cover structure is in place. In this way the cover structure becomes interlocked with the body structure, and, while it leaves the contents of the container exposed to plain view 80 and enhances the attractiveness of its appearance, it protects the contents against handling, deterioration and the like. The cover may be removed by grasping it in the 85 hand and raising it until it springs out of engagement with the lips d d.

Inasmuch as in the adaptation shown in Fig. 1 each container slightly overlaps the one below it, the assembling and disassembling may be facilitated by cutting away one 90 end of each lip d d, as at d' in Fig. 2.

The body structure shown is somewhat like that disclosed in my Patent No. 794451. It is preferred, however, that the two side 100 walls b b thereof be cut low, as already stated, partly to increase the exposure of the contents and partly to facilitate the assembling of the parts of said body structure. That is to say, the body structure is made 105 up of a piece of sheet material, as tin plate, j, having its lateral portions bent up to form said sides, and two outer pieces of similar material k having the lips d (aforesaid), the lips l, which underlie the part of the piece 110 j constituting the bottom of the structure, and the wings m m; these wings are secured

2
to the said sides by rivets, clips or the like *n*, and it greatly facilitates the placement of such clips, by rendering them more accessible, if the sides are cut low.

5 The edge portion of each side of the body structure is rebent, the rebending being outward to impart a finish to the same and not reduce the capacity of the box. In view of this each wing, in place of being a rectangular extension of the piece *k* is formed tapering and its extremity secured flat against the side of the body below its rebent edge, thus avoiding the formation of a corner which, if the wing were rectangular, would 15 be projected outwardly by the rebend when the wing is clenched in securing it.

Having thus fully described my invention, what I claim as new and desire to secure by Letters Patent is:—

20 1. In combination, an upwardly open box-like body structure and a cover consisting of a transparent top wall and two depending transparent side walls, said cover resting on the body structure and having its 25 side walls projecting higher than the sides of the body structure, substantially as described.

2. In combination, an upwardly open rectangular box-like body-structure having a 30 locking projection extending from the upper part of one of its upright walls inwardly beyond the inner surface of said wall, and a

rectangular transparent cover formed of sheet material and fitted into the body-structure from above, said cover having downwardly extending walls each bearing edge-wise against the upright wall of said body relatively opposite that wall of said body from which extends the projection and also having a top wall extending under said projection, whereby to necessitate bending of the cover in order to remove the same from the body-structure, substantially as described. 35 40

3. In combination, an upwardly open rectangular box-like structure having two opposite sides higher than the other two opposite sides and having one of the higher sides formed with an inward projection, and a transparent cover formed of stiff sheet material and resting on the body structure with its side walls coincident with and projecting above the lower sides of the body structure, said cover being held by the body structure against movement away from the side of said body structure having the projection and being engaged under the latter, substantially as described. 45 50 55

In testimony whereof I affix my signature in presence of two witnesses.

WILLIAM H. CLEMENTS.
